UNITED STATES PATENT OFFICE

RAYMOND J. NORTON, OF WASHINGTON, DISTRICT OF COLUMBIA, ASSIGNOR TO BENDIX AVIATION CORPORATION, OF SOUTH BEND, INDIANA, A CORPORATION OF DELAWARE

SEAPLANE

Application filed March 24, 1931. Serial No. 524,949.

This invention relates to seaplane steering means, and a major object of this invention is to provide a rudder for use on the pontoon or pontoons of the seaplane.

5 A further object of this invention is to provide means whereby such a rudder may be withdrawn within the surface of the pontoon to reduce the air or water resistance, when such action is desirable.

10 Yet a further object of my invention is to provide such a rudder as may be used in the air as a stabilizing fin or as an airfoil surface.

A still further object of my invention is the provision of suitable controls for such a 15 rudder, and the correlation of such controls with the other controls of the seaplane.

With these and other objects in view, which may be incident to my improvements, the invention consists in the parts and combinations to be hereinafter set forth and 20 claimed, with the understanding that the several necessary elements comprising my invention may be varied in construction, proportions and arrangement, without departing from the spirit and scope of the appended 25 claim.

In order to make my invention more clearly understood, I have shown in the accompanying drawings means for carrying 30 the same into practical effect, without limiting the improvements in their useful applications to the particular construction, which, for the purpose of explanation, have been made the subject of illustration.

35 In the drawings:

Figure 1 is a side elevation of a seaplane showing the invention installed;

Figure 2 is an enlarged detail showing the 40 features of the rudder and its operating mechanism;

Figure 3 is a detail of the manual controls;

Figure 4 is a sectional view taken on line 4-4 of Figure 3;

45 Figure 5 is an enlarged sectional detail of the mounting of the rudder;

Figure 6 is a sectional view taken on line 6-6 of Figure 5; and

50 Figure 7 is a diagrammatic view of the controls for the air and water rudders.

As shown in the drawings the invention may be applied to any type of seaplane or flying boat having a fuselage 1, air sustentation surfaces 2, propelling means 3 and empennage 4. Associated with the plane are the floats or water sustaining surfaces, illustrated in this instance by the pontoons, 5. These float members are attached to the fuselage in any suitable manner, as by the float struts 6, 7, and 8.

55 The pontoons may be of any suitable construction such as wood or light weight, high strength alloys of the duralumin type. Preferably the pontoon bottom is of stepped construction as shown at 9. Mounted on the 60 pontoon for vertical and angular movement with respect thereto is the rudder 10. This member may be constructed of any suitable material and of any desired shape and size 65 depending upon the steering effect desired, the ruggedness of the supporting structure, 70 the size of the plane and so forth.

75 As shown more particularly in Figure 2, the pontoon is provided with a recess 11, of the same general shape as the rudder, where- 80 in the rudder may be retracted when not in use. When so retracted, the bottom surface of the rudder forms practically a continuation of the bottom surface of the pontoon, thereby reducing to a minimum the fluid re- 85 sistance caused by the rudder.

The means for mounting the rudder are 90 shown in Figure 5. A bearing 12 is secured to a suitable rigid portion 13 of the pontoon. Mounted in bearing 12 is a sleeve 14, pro- 95 vided with a yoke composed of arms 15, and having a longitudinal squared recess extending throughout its length. Extending through the squared recess is a squared rudder post 16, upon the lower extremity of which is mounted the rudder 10. It will be noted that in the illustrated form, the rudder post is received in a similarly squared recess 17 in the rudder, and has a threaded extension 18 for receiving the securing nut 19.

At the top of the rudder post 16, and integral therewith, is a circular member 20, having a circumferential groove 21 therein. Cooperating with this groove are the pins 22, 100 mounted in the socket member 23. At the

top of this socket member ears 24 are formed, and a pin 25 extending therethrough connects the ears to a slot in the bell crank lever 26.

From Figure 5, the parts of which have just been described, it will be realized that operation of the bell crank lever 26 will cause the rudder port 16 to move upwardly and downwardly through the squared recess in sleeve 14, and consequently will retract or extend the rudder 10. Operation of arms 15 will turn the sleeve 14, and such angular motion will be transmitted to the post 16 and the rudder 10 through the squared connection, while the pins 22 move in groove 21.

15 A suitable system of controls is shown in Figure 7. Bell crank levers 26 are operated by cables 27, passing over suitably placed pulleys and connected to crank arms 28 located at the end of shaft 29, operated by a hand lever 30, located adjacent the pilot. Return springs 31 are provided for the bell crank levers and lever 30 may be provided with a pawl and ratchet or tooth and sector device, such as is commonly used on the hand braking levers of automobiles, for retaining the rudders in their retracted position.

30 The inner arms 15 of the rudder yokes are connected together by cable 32, led over suitably placed pulleys. The outer arms 15 are connected by cables 33, led over suitably placed pulleys, to crank arms 34 on the ends of shafts 35, operated by pedals 36. Mounted on shafts 35 are sleeves 37. On the inner ends of these sleeves are mounted pedals 38 and at the outer ends, crank arms 39. The ends of yoke 40 of the air rudder 41 are connected to crank arms 39 by cables 42, led over suitably placed pulleys.

35 Secured in shafts 35 are pins 43, cooperating with slots 44 in sleeves 37. By this arrangement, it will be seen from Figures 3, 4 and 7, that pedals 38 may be operated to control the air rudder without affecting the water rudders. When pedals 36 are operated to control the water rudders, however, the pins 43 will move sleeves 37 with shafts 35, and the air rudder will be operated conjointly with the water rudder.

40 If desired, the pin and slot arrangement 43, 44, may be dispensed with, and the adjacent lugs 45 removed from the pedals 36 and 38 (see Figure 3). The pilot may then operate the air rudder independently by placing his feet on pedals 38 only; he may operate the water rudder independently by placing his feet on pedals 36 only; and he may operate the rudders conjointly by placing each foot so it rests half on a pedal 36 and half on a pedal 38.

45 It is to be noted that the control cables 27, 32 and 33, leading to the water rudders, pass from the fuselage to the pontoons through the struts 7, thereby protecting the cables and reducing the air resistance of the plane.

The greatest utility of the water rudders is, of course, in steering the seaplane as it taxies over the water. These rudders, as previously stated may be retracted when the plane is on the water or in the air to reduce fluid resistance. If desired, the rudder may be left exposed in the air to serve as a vertical fin or as an aid to the other controls. Of course the water rudders are susceptible of various well known uses for a rudder, such as reducing speed by "fishtailing" the rudder back and forth.

50 While two pontoons and two rudders have been shown, various other arrangements and modifications are within the scope of the invention. Two similar rudders may be used on the single float of certain types of seaplanes, or a single rudder, with suitable changes as to size, etc., may be used on such a single float seaplane. In this latter case, cable 32 and its pulleys would not be necessary and the two cables 33 could be attached to the two arms 15 of the single rudder.

55 While there is shown and described a specific mechanism, it is to be understood that this is given merely as one embodiment which typifies the other equivalent mechanical structures by which the functions herein described may be secured and/or the desired results achieved.

I claim:

60 In a seaplane, an air rudder, a water rudder, means for operating said air rudder independently of the water rudder, and means for operating the water rudder, said water rudder operating means automatically co-acting with the air rudder operating means to actuate the air rudder; and means to retract the water rudder within the stream line contour of the seaplane.

65 In testimony whereof, I have hereunto signed my name.

RAYMOND J. NORTON.
